ATTORNEY

UNITED STATES PATENT OFFICE.

ISAAC T. RUE, OF BROOKLYN, NEW YORK.

TEA-POT.

SPECIFICATION forming part of Letters Patent No. 234,148, dated November 9, 1880.

Application filed September 13, 1880. (No model.)

To all whom it may concern:

Be it known that I, ISAAC T. RUE, a citizen of the United States, residing at Brooklyn, in the county of Kings and State of New York, 5 have invented a new and useful Improvement in Tea-Pots and similar articles; and I hereby declare the following to be a full, clear, and exact description thereof, reference being had to the accompanying drawings, which form 10 a part of this specification.

My invention relates, primarily, to an improvement in the lids of tea-pots, but it is also applicable to other vessels or articles which have lids that are frequently opened and 15 closed; and the object of my invention is to provide an improved metallic lid for a tea-pot having an earthenware body, the said lid being constructed in such a manner that it can be very readily applied, and will not fall off 20 or become displaced after being placed in position.

It is well known that earthenware vessels are preferable to those of metal for making decoctions of tea, and earthenware tea-pots 25 have been extensively used for that purpose; but these have ordinarily been provided with earthenware lids, which it is difficult, if not impossible, to fit securely to the body, and, consequently, the lids are liable to fall off and 30 break the cup or saucer while the tea is being poured out. Hinged metallic lids have also been used on earthenware tea-pots to some extent, but the difficulty of properly securing the hinge to the earthenware has rendered 35 them both expensive and unserviceable. By my improvement these difficulties are obviated, as the lid fits tightly to the body and does not require any special adaptation of the body to receive it, and at the same time I 40 thereby provide a neat, cheap, and ornamental article of household use.

The invention consists, first, in the improved construction of a metallic lid for an earthenware tea-pot or other vessel, as hereinafter particularly described; and, secondly, in an earthenware tea-pot or vessel provided with a metallic lid fitted in position by means of springs, as hereinafter set forth and described.

50 In the accompanying drawings, Figure 1

represents a side elevation of a tea-pot with my improvement; Fig. 2, a vertical section, on the line *x x*, of the body and lid; and Fig. 3, a view of the under side of the lid detached.

Similar letters of reference indicate the same 55 parts in all the figures.

A represents the body of a tea-pot, but, as before mentioned, my improvement may be applied to various kinds of vessels; and although my invention is more especially intended to be applied to vessels made of earthenware, it may also be applied to metallic vessels. The body may be of any convenient 60 and desirable shape, and no ledge or flange is needed to support the lid.

a represents the ordinary spout, and *b* the ordinary handle of a tea-pot.

B represents my improved lid, which is made of sheet metal stamped or pressed into the desired form, and provided with a knob, 70 *c*, of some material which is a non-conductor of heat, for lifting it on and off. On the under side of the lid are secured springs *d d d*, by which the lid is held to the body *A* when placed in position. Any desired number of 75 these springs may be employed, and their shape or form may be varied; but I prefer to use three upon each lid, and to make them of spring-wire, in the form shown in the drawings, with a ring or loop, *d'*, to impart additional elasticity. The free ends of the springs fit under the upper edge of body *A* when the lid is placed thereon, and thereby keep the lid 80 firmly in position so that it cannot fall off, and for that purpose the wire is bent so as to form 85 an angle or catch, *f*, that projects inside of the edge of the opening in the body.

It will be seen that no projections or ledges are necessary either to keep the lid in position or to adapt the body to receive the lid, 90 and hence the construction is extremely simple and inexpensive, as well as durable and not liable to breakage; and, also, that the opening in the body, being left plain, admits of the hand being introduced to wash it out 95 when necessary.

What I claim as my invention is—

1. A lid, *B*, for a tea-pot or similar vessel, *A*, made of sheet metal, and provided with spring-catches *d d' f*, for holding it in posi- 100

tion, and thereby dispensing with hinges and projections, substantially as shown and described.

2. A tea-pot or similar vessel having a body, 5 A, made of earthenware, and provided with a sheet metal lid, B, having spring-catches d d' f, which fit under the edge of the open-

ing in the body to keep the lid in position, substantially as shown and described.
